UNITED STATES PATENT OFFICE.

HENRY F. NEWBURY, OF NEW YORK, N. Y., ASSIGNOR TO ELEVATOR SUPPLY & REPAIR COMPANY, A CORPORATION OF ILLINOIS.

SWITCHING APPARATUS.

1,112,378.

Specification of Letters Patent. Patented Sept. 29, 1914.

Application filed January 28, 1905. Serial No. 243,120.

To all whom it may concern:

Be it known that I, HENRY F. NEWBURY, a citizen of the United States, residing in the borough of Brooklyn, city of New York, county of Kings, State of New York, have invented certain new and useful Improvements in Switching Apparatus, of which the following is a full, clear, and exact description, reference being had to the drawings accompanying and forming a part of the same.

This invention relates generally to switch devices and means by which such devices are operable, when in operable condition, the same being adapted for use in connection with electric switch devices, if desired, examples of which are hereinafter set forth in the drawings and specification.

This invention relates to apparatus for giving signals and it is illustrated as applied to an elevator system.

One of the objects of the invention is to enable signals to be given to a passenger at a floor indicating to him the cars which are approaching the direction in which he desires to go, and to provide such apparatus with an arrangement whereby when desired the cars can run without operating the signals.

A further object of the invention is to provide this mechanism with means for holding it in a set position so that it will maintain itself in a relation which will enable a car to run without giving any signals and without requiring the attention of the operator or starter to maintain that condition.

Further objects of the invention will appear more fully hereinafter.

The invention consists of the combinations of parts, members or devices hereinafter set forth and particularly pointed out in the claims which form a portion of this specification.

In the drawings which illustrate the preferred embodiment of my invention, Figure 1 shows diagrammatically and partly in front elevation the apparatus as arranged for a single car such as an elevator car; Fig. 2 is a plan view partly in section and on an enlarged scale illustrating parts of the apparatus shown in Fig. 1; Fig. 3 illustrates part of the same apparatus illustrated in

Fig. 2 but shows it in a different position or relation; Fig. 4 shows a portion of one of the switch devices and connected parts when the same has been actuated by the movement of a carriage or traveler; Fig. 5 shows one of the switch devices in end elevation; Fig. 6 is another view of one of the switch devices; Fig. 7 shows the same parts as those illustrated in Fig. 6 but represents the terminals as brought into contact to close the switch; Fig. 8 is a front elevation upon an enlarged scale of the carriage or traveler and connected parts illustrated in Fig. 1 but with certain of the parts in a different relation; Fig. 9 is a side view of the parts shown in Fig. 8; Fig. 10 shows in front elevation those parts seen in Figs. 8 and 9, but with some of the parts in different positions from those corresponding parts as seen in Figs. 1, 8 and 9; Fig. 11 shows in side view some of the parts seen in the upper portion of Fig. 9, but with the parts in the position seen in Fig. 10, which is different from the positions the same or corresponding parts occupy in Figs. 8 and 9; Fig. 12 illustrates in front elevation, and on an enlarged scale, one of the parts connected with the carriage which engages with the switch devices in position to be operated as the carriage moves in one direction, seen in preceding figures; Figs. 13 and 14 illustrate details of the operation of some of the parts as the carriage moves relatively to other portions; Fig. 15 illustrates in rear elevation a different construction and arrangement of parts forming a carriage adapted to be substituted for the one shown in Fig. 1, upon the substitution of the switch devices and bars, seen in Fig. 16, for each of those seen in Figs. 1 and 2; Fig. 16 shows in front elevation parts of two carriages and connected parts with two controllers of the general form seen in Figs. 1, 2 and 3 upon which the switch devices are mounted with a modified form of switch devices mounted thereon, a form which is well adapted for use in connection with the form of abutting or coacting surfaces seen in Figs. 17, 18 and 19 to engage with and actuate the same and move the controllers or bars, as in the construction seen in Figs. 1 and 2; Fig. 17 shows in side elevation the carriage seen in Fig. 15 and also a portion of the

frame of the apparatus on which the parts are mounted; Fig. 18 shows in front elevation that which is shown in rear elevation in Fig. 15 and in side view in Fig. 17, but with 5 each of the abutting surfaces and some of the parts shown in one of two positions in full lines and also in dotted lines; Fig. 19 shows the same parts seen in Fig. 18, but with the abutting surfaces seen in full lines 10 when in position for both to pass by the switch devices without actuating them in the up and down movements of the carriage; Fig. 20 illustrates the polarized relay and locking devices seen in Figs. 15 and 17, but 15 separated from adjacent parts and with the locking devices in the locking position to hold the abutting surfaces in the positions seen in Fig. 19, instead of in the unlocked positions, as seen in Figs. 15 and 17; Fig. 21 20 illustrates in front elevation another embodiment of the present invention wherein the abutting surfaces are not movable on their supports and portions of the switch devices or their coacting parts are made 25 movable into and out of coacting positions with the surfaces; Fig. 22 shows on an enlarged scale, in plan and partly in section, the parts seen on line 22—22 of Fig. 21, with the bar on which the switch device is mounted 30 not broken away, as seen in Fig. 21, such bar being in position for such device to be operative, being provided with one of the controlling magnets and armatures, used in connection with such bar as shown in Figs. 35 1 and 2, and by which the bar is held in the inoperative position or farthest away from the coacting or abutting surface which moves it to move the switch device itself out 40 of operative relation with the part, with which it contacts and brings the terminals thereof into contact; Fig. 23 shows a construction in front elevation, with some of the parts removed, in which a feature, not shown in Figs. 21 and 22, has been added 45 and by which the operative relations of the abutting surfaces and switch devices may be changed and held thus changed until it is desired to restore such relations; Fig. 23^a shows in plan view the armature lever seen 50 in Figs. 21 and 23; Fig. 24 shows in side view the parts seen in the upper portion of Fig. 23, when looking from right to the left, and the electromagnet at the upper right hand corner of such figure is omitted; Fig. 55 25 shows in front elevation portions of the parts seen in Fig. 23 separated from the other parts for clearness of illustration.

Like letters of reference, wherever they occur, indicate corresponding parts in all of the figures of the drawings.

A slab of slate or other desired material is preferably employed as a frame or mounting upon which the parts, including the switch devices, are suitably mounted and 65 which preferably are to be located at a cen-

tral, or other point, and are to be operated through the movements of the car or similar object, or by the mechanism by which the car is moved from one floor or station to another floor or station.

In Figs. 1 to 14, F represents a slab of slate or other material which serves as a frame on which other parts are preferably mounted. To this frame F there are attached two bars, Y Y', in which are mounted four bars, which may be hollow so as to form tubes D, D', D² and D³, which are free to slide lengthwise in guide bars Y and Y', as shown in Fig. 1. Each of these bars or tubes has mounted upon it a switch device, which may consist of a pair of terminals and means by which a coacting surface is enabled to bring such terminals into contact and close a circuit. There is, as here shown, one switch device for each bar or controller, as D, D', D², &c., and they are arranged to serve a single car, as such car moves in two directions relatively to the floors or stations to be served, one half of the controllers or bars and switch devices being for the up 70 movements and one half for the down movements of such car. These switch devices, B, B', B² and B³, are provided with pairs of terminals, as b, b', b², &c., respectively, which are insulated, one terminal 75 from the other, and these terminals form the terminals of circuits, respectively. Each controller or bar, as D and D', is movable back and forth in the bars Y and Y', and control the position or positions of some 80 portion of the switch device or devices relatively to another part or parts by which each pair of terminals may be closed and opened at desired times. As here shown the 85 switch devices are normally in an inoperable 90 or ineffective condition or position, that is, some portion or portions of each device is normally in such position, relatively to some other portion or portions thereof, so that the terminals will not be closed upon the up 95 and down movements of the car, but have to be moved, i. e. brought into position or condition where such movements will cause such pairs of terminals to be closed and opened. When such controllers are moved 100 by the segments of the eccentric gears into positions where the switch devices are in inoperative condition stops or detaining devices engage with the controllers to hold or 105 detain them with their switch devices in the 110 inoperative condition until such detaining devices are operated to release them. As 115 shown these stop or detaining devices consist of an armature, a spring, an electromagnet and suitable stop or engaging projections, arranged to engage and disengage 120 upon the movements of the armature, as seen in Figs. 2 and 3. In Fig. 2 the controller D' has been moved in the direction of the arrow thereon by the spring S' connecting 125 130

with the bar Y' and controller D' , as seen, that is, it has been moved from the position seen in Fig. 3 to that seen in Fig. 2 upon energizing magnet M' , overcoming spring M^{10} , Figs. 2 and 3, and withdrawing stop projection d'' , on armature m' , from engagement with stop pin or projection d' on controller D' and thus permitting the stress of spring S' to become effective and move the controller from the position seen in Fig. 3 to that seen in Fig. 2. Electromagnet M' is energized by means of a source of energy Z' , push button device P' and circuit wires 101, 104, 105 and 103, upon operating device P' , as in ordinary push button circuit closing devices. This push button device is to be located conveniently at the floor or station desired and is to be operated by the person at such floor or station to signal that the car is to stop thereat. On operating the push button P' magnet M' is energized and armature m' attracted, removing stop d'' from engagement with pin d' when the switch device is brought into the operative condition by spring S' . Each controller, as D D' , D^2 and D^3 , is provided with a magnet, as M , M' , M^2 and M^3 , armatures m , m' , m^2 and m^3 , push button devices, as P , P' , P^2 and P^3 , and circuits connecting with a source or sources of energy, respectively, as just described. Push button P is connected with magnet M and source Z' by wires 101, 102 and 103. Device P^2 is connected with the same source by wires 101, 106, 107 and 103, and device P^3 is also thus connected by wires 101, 108, 109 and 103. Two of these push button devices, it will be seen are to be operated to signal the car as it moves upwardly, and may be called "up" push buttons and two to signal as the car moves downwardly and therefore may be called "down" push buttons.

The carriage or traveler C is mounted to move relatively to and past the switch devices by means of guide rollers g , g' , g^2 , etc., carried on studs, as G , G' , G^2 , &c., Fig. 2. A reducing mechanism R connects with the operating mechanism W and reduces the speed and the distance moved by the carriage C as desired, accordingly as the constructor sees fit in constructing any given apparatus. A reduction by which the carriage moves about two inches while the car or similar object moves twelve feet has been found quite satisfactory in practice. Any desired form of speed reducing mechanism may be employed. Suitable forms of such mechanisms are well known in connection with mechanical indicators. Reducing mechanism R is connected with carriage C by any form of suitable flexible connecting material, as cord or rope z , and preferably in such manner that as car A moves upwardly carriage C also moves upwardly.

Carriage or traveler C is provided at

each end portion with a movable part or piece of the form and construction more clearly seen in Fig. 12, where one of such parts is seen detached and separate from the carriage. As thus seen each of these parts, c and c' , is provided with a roughened engaging surface preferably in the form of "rack teeth" which are adapted to engage with the segments of eccentric gears forming coacting parts and which are in turn adapted by their movement to cause the terminals of the switch devices to be closed and permit the same to be opened. Each switch device, as B , B' , &c., is provided with one of these segments of eccentric gears, as a , a' , a^2 , &c., which is pivotally mounted on studs, as h , h' , h^2 , &c., respectively, which are in turn mounted on controllers, as D , D' , &c., and hence are carried by such controllers in certain relations to the pairs of terminals as b , b' , b^2 , &c., respectively, also carried by the controllers. On these studs, as h , h' , &c., are also pivotally mounted parts, as a^4 , a^5 , a^6 and a^7 , respectively. These parts, as a^4 , a^5 , &c., are adapted to be engaged by projecting pins or portions, as j , j' , j^2 and j^3 on segments, as a , a' , &c., respectively, as seen in Fig. 6, and be moved from the position, seen in that figure, by the movement of the part as a^2 , into that seen in Fig. 4, by the engagement of the "rack teeth" on parts, as c and c' , with the segments as indicated in this Fig. 4, when such parts are moving in the direction of the arrow relatively to such segments. This movement of the rack in engagement with the segments causes the latter to turn on their respective studs, thereby causing the parts, as a^4 , a^5 , &c., to also turn thereon, which causes pins or projections thereon, preferably insulated therefrom, to engage with their respective pairs of terminals, closing the same, as clearly seen in Figs. 4 and 7. After the segments as a , a' , &c., have been moved into the position seen in Fig. 4 they naturally will not continue to turn on their respective studs, because the eccentricity of such segment will have forced the controller and segment away from the carriage sufficiently for the gear teeth thereon to be out of mesh with the teeth on the rack carried by the carriage, and the rack can continue its movement indefinitely without further effect on the segment, except possibly to hold it in the position seen in Fig. 4. Such eccentricity will also have forced the controller into position where the armature, as m , m' , &c., will be moved under the stress of its spring, as M^{10} , M^{10} , &c., from the position seen in Fig. 2 to that seen in Fig. 3. In this position its magnet will have to be energized to again bring the switch device into operative condition, that is, with the parts in the positions seen in Fig. 2. When the rack on the carriage has

4

moved beyond the segment a two arm spring, as h , h' , h^2 , &c., connected therewith, as seen in Figs. 4, 5, 6 and 7, returns such segment from the position, seen in Fig. 4 to that seen in Figs. 5, 6 and 7, but the part, as a^4 , a^5 , &c., cannot return with the segment owing to a retaining device, as T , T' , &c., which engages therewith and prevents such part returning far enough to 10 open the coating terminals, as seen in Fig. 7. The switch device and connected parts seen in these Figs. 4, 5, 6 and 7 are shown in the lower right-hand corner of Fig. 1 and the controller and attached parts 15 have been turned so as to bring the controller behind the attached parts. These two-arm springs, as h , h' , h^2 , &c., are arranged relatively to the hubs of the segments, as a , a' , &c., and parts, as a^4 , a^5 , &c., which are 20 mounted on studs, as h , h' , &c., as seen in Fig. 5. One arm of each spring acts on its respective segment by contact with a pin or projection, as l , l' , l^2 , &c., respectively, as seen in Figs. 4 and 5, the pin or projection, as i , i' , i^2 , &c., respectively, holding 25 the other arm of such spring against movement. When it is desired that the segment, as a , a' , &c., shall move in the opposite direction and from the position where 30 it is held by the two arms of such spring, the pin or projection, as l , l' , l^2 , respectively, moves in that direction and it moves the other arm of such spring with it, pin or projection, as i , i' , &c., respectively, holding 35 the arm of the spring, which was before moved, against moving, and, hence, such spring is adapted, not only to hold the segment, as a , a' , &c., in the positions seen in Figs. 5, 6 and 7, but also to return such 40 segment to such position whenever moved therefrom.

In connection with each switch device there is arranged a retaining device, as T , T' , T^2 , &c., which is provided with a shouldered portion, as t , t' , t^2 , &c., respectively, to engage with the movable part, as a^4 , a^5 , &c., respectively, as seen in Fig. 7 where portion t^2 is shown engaged with part a^6 , being directly over a portion of such part 45 preventing it from moving in a direction to open the pair of terminals b^2 , under the spring action of such terminals. This part, as t , t' , &c., is spring pressed against part, as a^4 , a^5 , &c., by a spring, as S^4 ; S^5 ; S^6 , &c., 50 as shown in Figs. 6 and 7; such part being movably mounted on the controller as D , D' , &c., as shown in these figures, so as to move longitudinally thereof. This retaining device is moved in opposite direction or away 55 from part, as a^4 , a^5 , &c., by inclined surfaces, as O and O' , mounted on the carriage C . Surface O serves to move portions t' and t^2 of retaining devices T' and T^2 out of engagement with parts a^5 and a^6 of switch devices B' and B^2 , and surface O' serves the 60

same purpose for portions t and t^2 of retaining devices T and T^2 of switch devices B and B^2 , whenever such portions, as t , t' , &c., are in engagement with their respective movable parts, as a^4 , a^5 , &c., thereby releasing such parts from the holding or retaining action of parts so that the spring action of the terminals will restore such parts to their normal positions, as seen in Fig. 6. Surface O engages with the free ends of the 70 shouldered portions of devices T' and T^2 nearest to the carriage or traveler, as such surface moves past the same after the rack c has operated segments a^4 and a^5 , and as such surface moves upward such shouldered portions are forced backward against the stress of the springs, as S^5 and S^7 , until the retained parts are released and are restored to their normal positions again. Surface O' serves to do the same for the portions t and 80 t^2 , in the downward movement of the carriage. In Fig. 1 surface O' is shown in position just before engaging with the free end of portion t^2 of retaining device T^2 , the rack portion c' of the carriage, in its downward movement, having operated segment a^2 and closed the terminals b^2 and part t^2 has engaged with movable part a^6 and, as thus 85 shown, is holding the terminals in the closed condition or position. As the carriage continues its downward course surface O' will force part t^2 backward, restoring the part a^6 and its terminals to their normal positions, as seen in Fig. 6, when the circuit connected 90 with such terminals will be opened, or restored to its normal condition. 95

Each pair of terminals, as b , b' , &c., is adapted to close a circuit, as here shown, and when so closed to operate a signal device in a car or similar object for a desired period 105 of time, or extent of movement of the car before the floor or station is reached, where the push button device is located which is operated. This extent of movement may be any amount desired, as the distance between two floors. Usually a distance in which the car can readily be stopped is chosen, and in practice this has been found to be less than twenty five feet, depending however upon the speed of the car. Only one signal device in the car is necessary to give the signals in both directions of movement, although more than one may be employed if desired. Signal device L in car A may be 110 of any desired form and construction. This device L is connected with each pair of terminals and a source of energy in any desired manner. As shown device L is connected with source Z and terminals b as follows: by wire 1 leading from such source to device L , from such device by wire 2 to one of the pair of terminals b , then from the other terminal of such pair by wire 3 back to source Z . Device L is connected with 115 such source and one of the pair of terminals 120 125 130

5 *b'* by wires 1, 2, and 4 and from the other of that pair of terminals by wires 5 and 3 back to such source. This device is also connected with such source and the pairs of terminals *b*² and *b*³, respectively, by wires 6, 7, and 8, 9, respectively, connecting with wires 2 and 3.

10 The construction thus far described is one form or construction of apparatus to which the present invention may be applied, it being shown and described to explain the manner in which my invention is applied in practice.

15 In the construction of apparatus shown in Figs. 1 to 14, inclusive, the carriage C is provided with movable abutments, engaging surfaces or parts *c* and *c'* movable transversely to the direction in which the carriage moves relatively to the switch devices, and they are moved back and forth, as the carriage changes its direction of movement, one being moved into operative position to engage with the coating parts of the switch devices, (which are in operative condition,) 20 that are to be operated as the carriage moves in the direction to accomplish this result. For instance part or surface *c* is moved into operative or active position as the carriage moves upwardly and out of such position as it moves downwardly, and part or surface *c'* is moved into operative position as the carriage moves downwardly and out of such position as it moves upwardly. As a result there is only one of the two parts or surfaces, *c* and *c'*, in operative or active position at a time, the other one being in the inoperative position, hence, as the carriage moves in either direction it gives the proper signals. Or, in other words, by this transverse movement of these parts *c* and *c'* of carriage C the "up" switch devices, in operable condition, are effectively operated only when the carriage moves upwardly and the "down" switch devices are not actuated to give signals, and vice versa. These abutments or parts *c* and *c'* are mounted on studs, as E, E', E² and E³, Fig. 9, fixed to base plate E⁴, and each stud has mounted upon its free end a pair of pins or projections, as *e*, *e'*, *e*² and *e*³, Fig. 8, which are arranged in lines transversely of the direction of movement of the carriage and sufficiently far apart to receive such parts, as indicated in Figs. 1 and 8, and permit them 55 to move as just described. These parts, as *c* and *c'*, are moved, as shown, in one direction by springs, as *s* and *s'*, Fig. 8, one spring for each part, and they are moved in the other direction by a longitudinally movable cam bar E⁵, the cam portions of which coact with projections, as *r*, *r'*, *r*² and *r*³ formed on parts, as *c* and *c'*, as clearly seen in Figs. 8, 9, 10 and 12. This cam bar E⁵ has formed on its edges two sets of cams or inclined surfaces which are adapted to coact with these

projections, as *r*, *r'*, &c., one set being formed on one edge to coact with projections *r* and *r'* and the other on the opposite edge to coact with projections *r*² and *r*³; the two sets being so positioned that when one set 70 is moving part, as *c*, into position to coact with the "up" switch devices the other set is permitting spring *s'* to move part, as *c'*, out of coacting position with the "down" switch devices. On a change in direction of the movement of the carriage the cam plate E⁵ is moved and the parts, as *c* and *c'* reverse their relation. Cams or inclined surfaces *r*⁴ and *r*⁵ engage with projections *r* and *r'* on part *c*, and force such part against the stress of its spring *s* into the position seen in Fig. 8, where the teeth thereon can engage with the teeth or segments *a*' and *a*², as the carriage moves upwardly. Cam surfaces *r*⁶ and *r*⁷ engage with projections 80 *r*² and *r*³ and move part *c'* against the stress of its spring *s'* into position where the teeth thereon, on the downward movement of such part will engage with the teeth on segments *a* and *a*², moving part *c'* from the position 85 seen in Fig. 8 to that seen in Fig. 1. Thus as this cam plate moves in either direction both of the parts *c* and *c'* change from one position to another by the action of the cam surfaces on the projections and the 90 springs *s* and *s'*. I provide means for mechanically controlling these racks *c* and *c'* automatically. This cam plate is caused to move in the direction of its length, to control parts *c* and *c'*, by means of two rock-shafts N and N' mounted in plate E⁴ on the carriage, one shaft and its connected parts moving cam plate E⁵ in one direction and the other shaft and parts moving it in the other direction. Rock-shaft N has two 100 arms *n* and *n'* and shaft N' has arms *n*² and *n*³. Arms *n* and *n*² are each provided with a projection or pin, as *n*⁴ and *n*⁵, which is received in slightly elongated holes or slots *o*⁴ and *o*⁵ respectively. Arms *n'* and *n*³ have mounted thereon spring pawls *n*⁶ and *n*⁷, respectively. These pawls are movable against the stress of their springs *n*⁸ and *n*⁹, respectively, and are prevented from moving in the other direction by pins or projections *n*¹⁰ and *n*¹¹, respectively, fixed to the arms *n'* and *n*³, respectively. From this arrangement each pawl is effective for one direction of movement only. From this it 110 results that as the carriage moves upwardly pawl *n*⁷ may pass an obstruction, which might otherwise cause the rock-shaft N' to be moved, without moving such shaft, and this is also the case with pawl *n*⁶ and rock-shaft N as the car moves downwardly. 115

The frame F, as seen in Fig. 1, has an obstruction or stud *o*⁶ secured thereto near its top edge and another *o*⁹ near its bottom edge, and two others *o*⁷ and *o*⁸ nearly midway between those at the top and bottom. Pawl 120

125

130

n^7 , as the carriage moves upwardly, may pass by stud or obstruction o^7 by moving on its supporting arm n^3 , as seen in Fig. 13, without moving rock-shaft N' , and also 5 may, in like manner, pass by stud o^6 ; and pawl n^6 , as the carriage moves downwardly, may also pass by studs or projections o^8 and o^9 with like result. After pawl n^7 has passed either one of the studs or obstructions o^6 or o^7 and the direction of movement 10 of the carriage has been reversed or changed the pawl n^7 , when it reaches the first one of these studs, engages therewith and partially rotates rock-shaft N' in its bearings 15 as seen in Fig. 14, until the pawl is moved sufficiently to pass out of contact with such stud or obstruction, thereby moving cam plate E^5 lengthwise thereof, with the effects described above. With this arrangement of 20 pawls and studs there may be placed as many studs or obstructions on the frame of the apparatus, intermediate of the top and bottom ones, near the end of movement in each direction of the carriage, as one may 25 think desirable.

If desired means may be employed to continue the movement of the cam plate E^5 after the pawls put it in motion and thus move it sufficiently to move the pawls some- 30 what farther than the engagement of them with their coacting studs would naturally move them, as, for instance, such as seen in Figs. 1, 8, 9 and 10, which consists of a spring pressed wedging part, as r^{100} or r^{110} 35 and inclined or wedge shaped surfaces formed, as shown, by constructing V shaped notches or depressions r^{101} and r^{102} or r^{111} and r^{112} in one edge of cam plate E^5 , near the lower end, as seen in the above figures. 40 A spring, as r^{103} or r^{113} , tends to force the wedge shaped part r^{100} or r^{110} into the extreme bottom of their respective notches when once entered therein, and consequently the cam plate, as E^5 , may be moved some- 45 what farther by this action of the part, as r^{100} or r^{110} , on the inclined surfaces of their notches than the plate is moved by the pawls and studs, as before explained. Of course the stress of the spring, as r^{103} , and the frictional contact of the part, as, r^{100} , with the cam plate has to be overcome when the part r^{100} is being moved out of one notch and into position to enter the other, but this is accomplished by the positive contact of one 50 of the pawls with its respective stud or studs. After the part, as r^{100} , has entered either of the notches the spring, as r^{103} , tends to force it into the bottom thereof and this action moves the cam plate in a direc- 55 tion the same as the pawl and stud moved it. In addition to this the part, as r^{100} , spring as r^{103} , and the notches form a holding means by which the cam and directly connected parts are held in either of two 60 positions, corresponding with the notches r^{101} and r^{102} . Also the frictional contact of the part, as r^{100} , upon the cam plate tends to hold such plate at any point it may be placed in the path of movement thereof, except when such part is acting on the inclined surfaces of the notches, as just explained. The operation of the part r^{110} , spring r^{113} and notches r^{111} and r^{112} upon the cam plate E , seen in Figs. 8, 9 and 10, is the same as it is on the plate seen in Fig. 75 1, notwithstanding the slightly different configuration or shape of the two parts r^{100} and r^{110} .

An arrangement is provided so that the cam plate may be so moved that neither one 80 of the pawls will be in position to contact with its respective studs or obstructions in the movement of the carriage up and down past the switch devices, if so desired. This may be accomplished in the manner now to 85 be described. When thus constructed the signal apparatus for a car may be rendered inoperative at will, that is, the normal operations be suspended, and remain inoperative for any desired period of time and then 90 rendered operative again without interfering with the bringing of the switch devices from their normal inoperative condition into an operative condition or position, and also without disturbing the condition, position or positions of such devices while the car and carriage continue their up and down movements, except, that, when such apparatus is rendered operative again, the switch devices in operable condition at the time are 95 actuated as they would have been before the apparatus was rendered inoperative, the operations of the means just described for changing the operative relations of the 100 switch devices and actuating means being 105 also temporarily suspended. Furthermore, the means by which the signal apparatus for a single car is rendered inoperative is adapted, as herein shown and described, to be held or locked in position or condition 110 to hold such apparatus inoperative by means other than those used to render the apparatus inoperative and then such holding or locking means may be operated and the apparatus rendered operative again. 115

The cam plate E^5 is made movable longitudinally for a greater distance than it is normally moved by the rock-shafts N and N' and it can therefore take on an extended movement in one direction as occasion requires, and such plate can move from either of the positions seen in Figs. 1 and 8 to that seen in Fig. 10, where the wedge shaped part r^{110} is shown entirely out of both of the notches r^{111} and r^{112} and bearing against the edge of such plate. This movement is brought about by the action of two armatures when their respective magnets are energized. 120

Plate E^4 of the carriage has attached to it 125

near one end, an electromagnet M^{10} and near the other end it has attached thereto another magnet M^{11} . Magnet M^{10} has an armature m^{10} pivotally mounted relatively thereto and provided with a projection or arm m^{12} , which enters an opening m^{14} in cam plate E^5 of sufficient size to receive it and permit it and the plate to move freely. Magnet M^{11} has an armature m^{11} which is provided with an arm or projection m^{13} which enters an elongated opening or slot m^{15} in this cam plate E^5 , as seen near the lower ends of Figs. 8 and 10. These magnets, by reason of the slot m^{15} in plate E^5 , do not move the plate to the same extent. Magnet M^{11} and its armature m^{11} can only move such plate into the position it occupies when part r^{110} is in notch r^{112} . This brings armature m^{10} sufficiently into the field of magnet M^{10} , for continuing the movement of the plate without further assistance from armature m^{11} until it is in the position seen in Fig. 10, the slot m^{15} in the cam plate permitting such plate to move. This movement of the cam plate E^5 causes the rock shafts to be rocked in their bearings into the positions seen in Fig. 10, where the pawls n^6 and n^7 are both moved into positions where neither can engage with its respective studs or projecting pieces, as o^6 , o^7 , o^8 , &c., in either direction of movement of the carriage and, hence, such pawls and studs no longer coact to change the relations of the switch devices and the means which actuate them, the normal operation of such pawls and studs being suspended or interrupted until such pawls resume their former positions relatively to such studs. Also the parts or surfaces of the carriage, c and c' , will both be moved into the positions seen in Fig. 10, where neither one can engage with any segment or segments which it might engage with but for this extended movement of the cam plate in this direction. This is accomplished by the action of the springs s and s' and cut away portions on the cam plate E^5 which permits one of the two abutments or parts c or c' to move under the stress of its spring or springs and the other one to remain in the position it occupied at the time. These cut away portions r^{20} , r^{21} , r^{22} and r^{23} are clearly seen in Figs. 8 and 10. As seen in Fig. 10 the projections or pins r and r' on part c are in cut away portions r^{20} and r^{21} and the pins r^2 and r^3 on part c' are in cut away portions r^{22} and r^{23} . The parts will thus remain so long as the magnets remain energized and, then, when the magnets are deenergized such parts will resume a position where one of the rock-shafts will be in position for its pawl to be operative on its respective studs and the apparatus to be put into the operative condition again.

Sometimes it is desirable that the signal apparatus shall be temporarily rendered inoperative for a longer or shorter period of

time. It is not always desirable in such cases that the electromagnets shall remain energized for too great a length of time, where currents of electricity are used, such as are usually employed in operating signal devices in signal apparatus of the general class used in connection with elevator cars in buildings. If the time be short, as when the car has begun its trip and the apparatus be rendered inoperative until the completion thereof, then the magnets may remain energized for such a period of time, if properly constructed, and this may be accomplished by holding the circuit closed by the means which closes such circuit. If the time be longer, as, for instance, when a car is to be withdrawn from regular passenger service, as for repairs or other use, temporarily, and it is to be moved up and down in the shaft without receiving signals, then the apparatus may be made inoperative, that is the operation of the system for that car be suspended by the closing of the circuit and be held or maintained inoperative by other means than by holding such circuit closed.

Magnets M^{10} and M^{11} are connected in series with a source of energy, as Z , and to a push button or push buttons, as follows: A pole changer and polarized relay are placed in circuit therewith for a purpose to be hereinafter described. As here shown a push button P^8 is placed in the car A , and from wire 1, leading from source Z to signal device L in the car, a wire 10 connects with such push button; from this push button P^8 a wire 11 leads to the pole changer P^{10} and thence, when the arms 12 and 17 thereof are in the positions seen in full lines, to arm 12 of the pole changer and thence by wire 13 to the coil of the polarized relay M^{20} , wire 14 to electromagnet M^{10} , wire 15 to magnet M^{11} , wire 16 to arm 17, of the pole changer, and from such arm to wire 18, to wire 3 and back to source Z . The operation of this portion of the apparatus is as follows: Upon the operator in the car wishing to render the signal apparatus of his car inoperative temporarily, as for a portion of a trip, he operates the push button P^8 , closes the circuit from source Z , through the pole changer P^{10} , coil of relay M^{20} , magnets M^{10} and M^{11} back to the pole changer again and source Z , energizing magnets M^{10} and M^{11} and moving cam plate E^5 into the position seen in Fig. 10, as before explained. So long as the circuit is thus closed the cam plate will be held in this position and the other parts will remain in the positions there seen. Assuming that the current in the circuit was in a direction for polarized relay M^{20} to hold its armature m^{20} in the position seen in Fig. 9 and releasing the push button P^8 the circuit would be broken and then the cam plate and connected parts

would assume positions where one of the pawls, as n^6 , n^7 , would be operative upon its respective stud or studs, when the apparatus would operate as before the push button was actuated, that is the normal operation would be resumed. This movement of the cam plate and connected parts, when magnets M^{10} and M^{11} are deenergized is caused by a spring S^8 and connected pin 10 s^9 , clearly seen in Figs. 9 and 11. Pin s^9 is arranged in position for projection or pin m^{12} on armature m^{20} to contact with and move it, when magnets M^{10} and M^{11} are energized, and compress spring S^8 , so 15 that when such magnets are deenergized the spring will act to return the parts, as above described. As shown in Fig. 1 a second push button P^9 is arranged outside of the car and it may be located at the 20 main floor of the building where the person in charge of the elevators is usually stationed, so that it may be operated at that point and render the signal apparatus for a single car inoperative and then the 25 operator in the car will not receive any signals to stop at any of the floors or stations and may continue his course. This push button P^9 is connected to wire 1 by wire 19 and to wire 11 by wire 20, and 30 consequently the actuation of such button has the same effect as the actuation of push button P^8 , in rendering the apparatus inoperative, and holding it inoperative.

The apparatus, as here shown, may be 35 held inoperative for the desired length of time by means of the polarized relay M^{20} and connected parts. The armature m^{20} of relay M^{20} is free to move between the poles m^{21} and m^{22} and it is moved into the position seen in Fig. 9 as the current passes 40 through the coil in one direction, and the pin or detent m^{23} on armature m^{20} is held out of engagement with the detent pin m^{24} on armature m^{10} of magnet M^{10} , so that 45 armature m^{10} can move back and forth without being interfered with by detent or holding device m^{23} on armature m^{20} of relay M^{20} , so long as armature m^{20} is thus held. This armature m^{20} is moved into 50 the position seen in Fig. 11 upon a reversal in the direction of the current in the coil of relay M^{20} when armature m^{10} is in position to permit armature m^{20} to assume the position therein seen. When the parts 55 are in the position seen in Fig. 11 and the circuit is broken the stress of spring S^8 acts on pin m^{12} and forces detent pin m^{24} , carried by armature m^{10} , against holding device or detent m^{23} on armature m^{20} and 60 as pin m^{12} engages with cam plate E^5 such plate cannot move under the stress of spring S^8 farther than such detent m^{23} will permit and the signal apparatus is held inoperative until detent m^{23} is removed or 65 returns to the position seen in Fig. 9. Upon

a change of the arms 12 and 17 of the pole changer P^{10} from the positions seen in full lines to those seen in dotted lines the direction of the current through the coil of relay M^{20} and magnets M^{10} and M^{11} is reversed, upon operating either of the push buttons P^8 or P^9 , from what it is when such arms occupy the positions seen in full lines. This pole changer may be of any desired form and be located at any desired point, so long as it accomplishes this work in the apparatus. As shown, it is assumed to be located adjacent to push button P^9 and operable from the same point that the button is operable.

When it is desired to render the apparatus for a single car inoperative for a considerable period of time the pole changer P^{10} is operated and its arms 12 and 17 are moved from the positions seen in full lines to those seen in dotted lines and then upon either push button, as P^8 or P^9 , being operated the circuit is closed as before, but the direction of the current is reversed. This reversal does not change the operation of armatures m^{10} and m^{11} upon cam plate E^5 , but does change the movement of armature m^{20} of relay M^{20} and its direction of movement is reversed and it is moved from the position seen in Fig. 9 to that seen in Fig. 11, then when the circuit is broken the parts are held in the positions seen in Fig. 11 until the pole changer is again changed and the circuit again closed when armatures m^{10} and m^{11} will be attracted toward their magnets and armature m^{20} will be moved from the position seen in Fig. 11 to that seen in Fig. 9, and then upon the breaking of the circuit and deenergizing the magnets armatures m^{10} and m^{11} with cam plate E^5 can move under the stress of spring S^8 to the position seen in full lines in Fig. 9, and the apparatus is operative as before.

From the foregoing it will be seen that there are two kinds of means by which the coacting relations of the switch device or devices may be changed and also that there is holding means consisting of the polarized relay and connected parts. Also that the second means control the first in that such second or additional means suspends the operation of the first and holds the parts of the second means in the changed positions for an indefinite time and without otherwise interfering with the first means than temporarily suspending the normal operation of the same.

Other forms of switch devices and actuating means than what is shown in Figs. 1 to 14 may be employed, if desired, that is, switch devices of the character of those seen in Figs. 21, 22 and 23 may be used or devices of the character, shown in Fig. 16, or of any other desired form or character, accordingly as the constructor of any given

apparatus desires. Also any desired form of actuating means may be employed which are suitable to coact with the particular form of switch devices used and operate the 5 same to open and close the circuits, as, for instance, actuating means of the character shown in Figs. 21, 22 and 23 may be employed to coact with the form of switch devices therein shown, or with any other 10 form adapted for use therewith and do this work, or means such as are shown in Figs. 15, 16, 17, 18 and 19 may be employed to actuate the form of switch devices indicated in Fig. 16, or any other form with which 15 such means will suitably coact to close and open the circuits. Or other forms than herein shown may be employed so long as they are adapted to do the work of opening and closing circuits and some portion or 20 portions of either the switch devices or the actuating means are made movable to change the coacting or operative relations of one relatively to the other, or the operative relations be changed by devices or members 25 combined together in substantially the manner and having the characteristic mode of operation of any of these combinations herein set forth and particularly pointed out in the claims hereunto annexed.

30 Instead of the means for changing the coacting or operative relations of the switch devices and actuating means seen in preceding figures the devices and means, seen in Fig. 16, may be substituted for those seen 35 in Fig. 1, that is, the carriage and abutting surfaces seen in Figs. 15, 16, 17 and 18 may be substituted for the carriage C, seen in Fig. 1, and the switch devices seen in Fig. 16 may be substituted for those seen in this 40 Fig. 1, of course, the dimensions of the parts being suitable to do this. When the switch devices seen in Fig. 16 are thus substituted there will be controllers and switch devices for two cars, one for each of the carriages 45 C¹ and C². To operate such switch devices and controllers the parts and connections seen in Fig. 1 would be duplicated for the second carriage or car to make the two correspond, one with the other. The mode of 50 operation in such case would be substantially the same, as hereinbefore set forth, notwithstanding the different constructions of parts in the two carriages and the two forms of switch devices.

55 In Fig. 16 two controllers or lengthwise slidable bars, as D⁴ and D⁵, are seen each having two switch devices, as B⁴, B⁵, and B⁶, B⁷, respectively. These controllers, as D⁴ and D⁵ are mounted in bars, as Y² and Y³, so as to be moved back and forth therein, as controllers D, D' and D², in Figs. 1, 2 and 3 do, and they are to be retained in position where the switch devices are in the inoperative condition and are to be moved 60 therefrom into operable condition by sub-

stantially the same means as are employed in such figures. As shown in Fig. 16 controller D⁴ is in the position it and switch devices B⁴ and B⁶, mounted thereon, occupy when the carriage, as C², in moving upwardly, as indicated by the arrow thereon, is just upon the point of leaving or passing by and beyond the movable or coacting part of switch device B⁶ and after having moved such controller and switch devices a distance 70 equal to that between the end of the abutment in its inclined position and a straight line parallel to the direction of motion of the carriage C² and passing through the point where the abutment first engages with 75 movable part a¹², which is sufficient in extent for such part a¹², as the carriage moves upwardly, to swing on its pivot and move out of a position where the abutment on the carriage would engage therewith on its next 80 upward movement, unless controller D⁴ had been in the meantime moved to the left to the position from which it was moved by the first upward movement to the one seen in Fig. 16. These switch devices, as B⁴, B⁵, 85 &c., like switch devices, as B, B', &c., are normally in an inoperative condition and are moved into an operative condition, or a position where they are operable by the devices carried by the carriage, as it moves 90 up and down past the switch devices, as is fully explained in connection with the switch devices and controllers seen in Figs. 1 to 14.

95 The carriages, one for a car as C' and C² seen in Fig. 16, one of which is seen in Figs. 15, 17, 18 and 19 on an enlarged scale are provided with abutments or abutting surfaces, as c², c³, c¹⁶ and c¹⁷, which, when in operative or coacting relations to the switch 100 devices, are inclined to the direction of movement of such carriages upon which they are mounted. As here shown only one of such abutments on each carriage is in this inclined or operative position at a time the 105 other one being then substantially parallel with the direction of movement of its respective carriage. As seen in Fig. 16 abutment or part c² of carriage C' is shown in this substantially parallel position, as such 110 carriage moves in the direction of the arrow thereon, abutment or abutting surface c³ being seen in the inclined position, so as to engage with part a¹¹ of switch B⁵, close the 115 circuit through part a¹¹ and spring b⁸ (the two open terminals of such circuit) and then force controller D⁵, by the inclined surface c³ acting on part a¹¹, to the left, as such carriage C' continues its movement downward, thereby operating and doing the same work 120 that is done by carriage C² in moving upward, and also the same work done by segments, as a a', &c., in connection with parts as a⁴, a⁵, &c., in Figs. 1 to 14. These abutments, engaging surfaces or parts, as c², c³, 125

&c., and carriages form actuating means, or means by which the switch devices for two cars are actuated to close the signal circuits. These parts, as a^{10} , a^{11} , &c., when 5 the controllers, with the switch device or devices mounted thereon, are in positions to bring the device or devices into operable condition, are engaged by the inclined surfaces or abutments on the carriages and by 10 reason of such parts being pivotally mounted on such controllers necessarily force them lengthwise away from the central line of movement of the carriages where the switch devices carried by the controllers are out of 15 operable condition, that is, in their inoperable condition, the inclined abutment on either carriage moving its respective controller with the switch devices carried thereby for both cars into the inoperable condition or position. Such parts, as a^{10} , a^{11} , &c., may form one terminal of each of the 20 circuits the other terminal being formed by springs, as b^4 , b^5 , &c., and thus each part and its respective spring will form a pair 25 of terminals for a circuit, as the pairs b , b' , &c., do, which, when brought into engagement, one with the other, operate substantially as each of the pairs b , b' , &c., operate. The inclined or abutting surfaces, in operating 30 the switch devices engage with the ends of the parts, as a^{10} , a^{11} , a^{12} , &c., farthest from the terminals, as b^4 , b^5 , b^6 , &c., and are moved into substantially a horizontal position, as part a^{12} is shown in Fig. 16, bringing 35 the opposite ends thereof into contact with their respective terminals, and, as the carriage continues its movement, either up or down, as the case may be, the sliding bar or controller carrying the switch device, 40 whose movable part, as a^{10} , a^{11} , &c., is in engagement with its coacting abutting surface, is forced away from the central line of movement of the carriage until it has reached a point where such surface moves 45 beyond such movable part, where the bar or controller may be detained or held by any suitable means, as, for instance, such as is shown in Figs. 1, 2 and 3, or any other desired means, until released and moved into 50 position for such surface to again engage with the movable part and repeat the above operation. There are two of these abutting surfaces on each carriage, as c^2 , c^3 , c^{16} and c^{17} , Fig. 16, and they are movable upon the 55 carriages as C' and C^2 , and are adapted to move into and out of engaging position relatively to the movable parts of the switch devices, so that as the carriage moves upwardly, or in the direction of the arrow 60 near top of Fig. 18, such surfaces or abutments occupy the positions there seen in full lines and then, when the direction of movement of the carriage is reversed these abutments or surfaces change positions and are 65 moved from those seen in full lines to those

seen in dotted lines in this Fig. 18. In this way only one abutment or surface on each carriage is in position to engage with the movable part or parts of the switch device or devices, in operable condition, and actuate 70 the same and move the controller and switch devices for two cars into inoperable condition, the other abutment or surface being substantially parallel with the direction of movement of the carriage. These abutments or abutting surfaces c^2 and c^3 of carriage C' , seen on an enlarged scale in Figs. 17, 18 and 19, are pivotally mounted on studs, as e^4 and e^5 , respectively, and are connectible and disconnectible with parts c^4 80 and c^5 , respectively, which are also pivotably mounted on the same studs e^4 and e^5 , which in turn are fixed in the main plate E^6 of the carriage C' . These parts c^4 and c^5 are substantial duplicates of one another, 85 and in this respect are like abutments c^2 and c^3 . The parts c^4 and c^5 are between abutments c^2 and c^3 , respectively, and the plate E^6 , as seen in Fig. 17, and one of them, part c^4 , is seen in Fig. 19, where the abutment c^2 is disconnected therefrom and moved into substantially a parallel position. Abutments c^2 and c^3 are connectible and disconnectible from parts c^4 and c^5 , respectively, by pins c^6 and c^7 fixed to abutments c^2 and 90 c^3 respectively, and detents or latches c^8 and c^9 pivotably mounted in parts c^4 and c^5 , respectively. Detents c^8 and c^9 are movable relatively to pins c^6 and c^7 , respectively, and are moved toward and into engagement 95 therewith by springs s^4 and s^5 , respectively, Figs. 18 and 19, which are connected with parts c^4 and c^5 , respectively, at one end, and to rods c^{10} and c^{11} , respectively, at their other ends. These rods c^{10} and c^{11} are mounted 100 to move endwise by being pivotably connected to detents c^8 and c^9 , respectively, and slidable in bearings formed in parts c^4 and c^5 , respectively. These rods c^{10} and c^{11} are bent at substantially a right angle at their 110 ends farthest from detents c^8 and c^9 and are moved against the stress of their springs s^4 and s^5 , respectively, by spring pieces p^4 and p^5 attached to pivotally mounted levers p and p' , which are movable in one direction 115 by the armatures m^{30} and m^{31} of electromagnets M^{30} and M^{31} , respectively, and in the other direction, when the parts are constructed and arranged as here shown, by gravity and a spring, as p^6 , seen at the lower 120 portion of Fig. 17. Gravity causes armature m^{30} and lever p to move downward and permit spring s^4 to move rod c^{10} and detent c^8 into engagement with pin c^6 , when the carriage moves vertically, and spring p^6 125 causes the armature m^{31} and lever p' to move upward and permit spring s^5 to move rod c^{11} and detent c^9 upward into engagement with pin c^7 , as occasion requires. This spring p^6 moves armature m^{31} upward by 130

means of a rod p^9 , of suitable material attached at one end to armature m^{31} and passing through a central opening in magnet M^{31} , in a well known manner, and its free end engaging with lever p' as seen in Fig. 17. This rod guides and supports the armature m^{31} in its movements, when magnet M^{31} is energized and deenergized. Armature m^{30} is provided with a similar rod p^8 which serves the same purpose as is served by rod p^9 , as just described. These rods p^8 , p^9 and the manner of their connection with their respective armatures and passing through magnets M^8 and M^{31} is clearly seen in Fig. 20.

The detents c^8 and c^9 have a portion which extends beyond the pins c^6 and c^7 , respectively, as shown, against which the pins may engage and force the detents against the stress of springs s^4 and s^5 , respectively, into positions so that such pins may engage therewith and fasten the abutments, as c^2 and c^3 , to the parts, as c^4 and c^5 , respectively, whenever either of said abutments is disengaged therefrom and free to move under the stress of their respective springs S^{12} and S^{13} . These detents, as c^8 and c^9 , with their connected parts by which the abutments or surfaces, as c^2 and c^3 are disconnected and connected with the parts, as c^4 and c^5 form means by which the operations of the parts which move such abutments as above described, are temporarily suspended and permit other means to control such abutments. These abutments, as c^2 and c^3 , are constructed with right angle portions, as c^{12} and c^{13} , more clearly seen in Figs. 17, 18 and 19, with which springs S^{12} and S^{13} , respectively, are connected at one end, the other ends of such springs being connected with main plate E^6 , as shown. These springs tend to move such abutments into their inclined positions, when free from the control of parts c^4 and c^5 , which are pivotally mounted on the same studs e^4 and e^5 , respectively, as the abutments are mounted. These abutments are moved by reason of their being connected with parts c^4 and c^5 and through the agency of slots c^{14} and c^{15} (Fig. 19) therein and pins or projections n^{16} and n^{17} on arms n^{14} and n^{15} of rock shafts N^{10} and N^{11} which work in such slots and cause parts c^2 and c^3 to move as such rock shafts move. These rock shafts are journaled in bearings in main plate E^6 and supplementary plate E^9 , as shown in Fig. 17, and are provided with supplemental arms n^{18} and n^{19} , respectively, which are connected together by a link n^{20} , so as to move together, that is, so that both move when either one of such rock shafts N^{10} or N^{11} move. Each of these rock shafts is provided with a third arm at one side of supplemental plate E^9 , as n^{22} and n^{23} , respectively, Fig. 15, which in turn is provided with a spring pressed pawl, as n^{24} and n^{25} , respectively. Each pawl is

provided with a spring, as n^{26} and n^{27} , respectively, also with a stop pin, as n^{28} and n^{29} , respectively, to permit the pawl to move against the stress of its spring and prevent its movement in the opposite direction, substantially in the manner the spring pressed pawls n^6 and n^7 operate in Figs. 8, 9 and 10. These pawls n^{24} and n^{25} coat with studs, obstructions or projections affixed to the frames of the apparatus as do the corresponding pawls in Figs. 1, 8, 9 and 10, that is, as the carriage C' moves in one direction one of such pawls is in position to contact with its respective stud or studs, and either pass by without actuating its rock shaft, or to engage and operate such shaft, as the case may be, and also when one rock shaft is actuated its movement operates the other one, changing its pawl from a position where it will not contact with and be moved by its respective stud or studs into a position where it will engage therewith, and moving into contacting or engaging position, as the other pawl moves out of such position, by reason of a direct engagement with its respective stud or obstruction. These pawls n^{24} and n^{25} , like pawls n^6 and n^7 , are arranged to operate and pass by the stud or studs without actuating the rock shafts for one direction of movement, but for the other direction of movement they will engage therewith; this is a preferred arrangement because it is the preferred way of arranging them and permits any desired number of studs or obstructions to be placed in their path of movement without actuating the rock shafts. If arranged to engage with the first stud met with in such path and actuate the rock shafts, then this movement of the shafts would occur just before the carriage reached the end of its movement in each direction, and this would interfere with the use of intermediate studs or projections between those at or near the ends of the movement of the carriage. These rock shafts and their connected parts mounted each on the carriage form a portion or portions of the means by which the coacting or operative relations of the switch device or devices and actuating means are changed, as in the construction seen in preceding figures of the drawings. Studs or obstructions, as o^{10} , o^{11} , o^{12} &c., may be employed in connection with these pawls n^{24} and n^{25} , and their connected parts, if desired or if this carriage C' be substituted for that of Fig. 1, then the studs shown therein may coat with these pawls n^{24} and n^{25} , as pawls n^6 and n^7 coat therewith, and with like results.

As shown, the rock shafts N^{10} and N^{11} may be moved somewhat farther in their direction of rotation than they would naturally be moved by the engagement of pawls n^{24} and n^{25} with studs or projections, as o^{10} , o^{11} , &c., Fig. 15, by means of the elbow levers 130

r^{120} and r^{121} coacting with the extensions r^{122} and r^{123} of arms n^{22} and n^{23} , respectively. These elbow levers r^{120} and r^{121} are connected together by a spring S^7 , so that the stress of such spring tends to force the beveled or wedge shaped ends of these levers against the beveled or inclined surfaces of extensions r^{122} and r^{123} and thereby move such extensions and the arms n^{22} and n^{23} away from the elbow levers turning the rock shafts in their bearings somewhat until the stop pins r^{124} and r^{125} , in supplemental plate E^9 , for levers r^{120} and r^{121} , prevent further movement of such levers. These levers r^{120} and r^{121} act somewhat as do the lever and bar on which wedge shaped parts r^{110} , r^{111} and r^{112} are formed and with like effect on the rock shafts.

As seen in Fig. 20 the armatures m^{30} and m^{31} of magnets M^{30} and M^{31} are locked in position to hold them against returning to their normal positions, when these magnets are deenergized, by pieces of suitable material, as m^{42} and m^{43} , attached to armature m^{40} of polarized relay M^{40} . This armature m^{40} is pivoted at m^{41} , so as to freely move between poles m^{44} and m^{45} of relay M^{40} . In Figs. 15 and 17 the armatures m^{30} and m^{31} of magnets M^{30} and M^{31} are seen in their normal positions, as when such magnets are deenergized with its armature m^{40} of relay M^{40} in the position for pieces m^{42} and m^{43} to be out of engagement with armatures m^{30} and m^{31} , and these armatures may move back and forth as the magnets are energized and deenergized without hindrance from pieces m^{42} and m^{43} of armature m^{40} , so long as the current passes in a direction through the coils of the relay and electromagnets to hold the armature m^{40} substantially in contact with pole m^{44} of relay M^{40} , as seen in Fig. 15. When the current is reversed and the armatures m^{30} and m^{31} are attracted by their respective magnets the armature m^{40} will be moved substantially into contact with pole m^{45} of the relay, as seen in Fig. 20, and the pieces m^{42} and m^{43} be moved in between armatures m^{30} and m^{31} and they cannot return, when magnets M^{30} and M^{31} are deenergized, to their normal positions until armature m^{40} is moved over toward pole m^{44} sufficiently for armatures m^{30} and m^{31} to pass by the ends of pieces m^{42} and m^{43} , respectively. Whenever it is desired to release or unlock these armatures m^{30} and m^{31} the current is put through the circuit in a reverse direction, (in any well known or desired way, as for instance, by a pole changer and push button, as shown in Fig. 1) from that in which it passed when the parts were brought into the positions seen in Fig. 20, and then upon the breaking of the circuit and deenergizing magnets M^{30} and M^{31} the parts will assume the positions seen in Figs. 15 and 17. When magnets M^{30} and

M^{31} are energized and the parts are brought into the positions seen in Fig. 20 the abutments or abutting surfaces c^2 and c^3 will be unlocked, (by the movement of rods c^{10} and c^{11} and the withdrawal of detents c^8 and c^9) or disengaged from parts c^4 and c^5 upon the initial or first portion of the movement of levers p and p' and then, when the free ends of these levers as p^2 and p^3 , engage with the portions c^{12} and c^{13} of abutments c^2 and c^3 , respectively, such abutments will be moved against the stress of springs S^{12} and S^{13} and be brought into the positions seen in full lines in Fig. 19. When this is done the parts c^4 and c^5 remain in the positions they were at the moment, when these magnets were energized, but they continue moving into and out of inclined and parallel positions just the same as if such abutments c^2 , c^3 had not been disengaged therefrom.

It is to be observed that in Fig. 18 the parts or pins p^2 and p^3 of levers p and p' stand some little distance from portions c^{12} and c^{13} of abutments c^2 and c^3 , while the spring portions p^4 and p^5 attached to such levers are substantially in contact with the angle end portions of rods c^{10} and c^{11} . Consequently upon the first portion of the movements of such levers, by the movements of armatures m^{30} and m^{31} upon the energizing of the magnets, these rods are moved endwise withdrawing detents, as c^8 and c^9 , out of engagement with pins, as c^6 and c^7 , attached to abutments c^2 and c^3 and holding them withdrawn until such levers p and p' return to their normal positions. After these detents are thus withdrawn the ends p^2 and p^3 of such levers may engage with the angle portions c^{12} and c^{13} of the abutments and move the abutment which is, at the moment, in an inclined position into substantially the parallel position and hold it, with its companion abutment, in the parallel position, as shown in Fig. 19. These parts or ends, p^2 and p^3 , of these levers p and p' hold both abutments in the substantially parallel positions, as shown in Fig. 19 so long as such levers are held in position by the magnets being energized, or by the armatures of such magnets being held in substantially the attracted positions by the armature of the polarized relay, as seen in Fig. 20. The result of moving the abutting or coacting surfaces, as c^2 and c^3 , into the positions seen in Fig. 19, and holding them in such positions is the same as in the case of parts c and c' in Figs. 1, 8, 9 and 10, and the mode of operation is essentially the same in each case. In fact the two are so nearly identical in mode of operation that the construction of carriage, as C' or C^2 , and connected parts seen in Figs. 15 to 20 may be substituted, as before explained, for the construction of carriages and connected parts shown in Fig. 1,

by simply connecting the wires 13^a and 16^a seen in Fig. 15, with wires 13 and 16, (through binding posts 13^b and 16^b,) seen in Fig. 1, upon the substitution of one for the other. Wire 13^a, seen in Fig. 15, connects binding post 13^b with magnet M³⁰, which in turn is connected with the coils of relay M⁴⁰ by wire A^x, which coils are connected with magnet M³¹ by wire A^y and such magnet is connected to binding post 16^b by wire 16^a. The armature m⁴⁰ of this relay M⁴⁰ and connected parts form a holding or locking device. The polarized relay and its connected parts form holding means by which the coacting relations of the switch device or devices and actuating means are held, when once changed. The magnets M³⁰ and M³¹, the polarized relay and connected parts form additional means by which the coacting or operative relations between the switch device or devices and actuating means are changed, and which control such relations as desired. Such additional means remain dormant or inert during the normal operation of the apparatus.

Instead of moving the coacting or abutting surface or surfaces carried by the carriage or actuating means, as shown in preceding figures of the drawings, a portion or portions of the switch device or devices may be moved, as indicated in Figs. 21 to 25 inclusive, without materially altering the mode of operation of changing the coacting relations of the switch devices and actuating means, one relatively to the other, whether this be done at different or stated points in the travel of one relatively to the other, at will, or otherwise. Also, instead of changing these coacting or operative relations by mechanical means operating as heretofore described such relations may be changed by other means as by electrical devices largely, as shown in Figs. 21 and 22, wherein movable contact devices are shown which are adapted to make electrical contact with relatively fixed contact devices, as the actuating means are moved in one direction and not to make such contact as such means move in the other direction. In Figs. 23 to 25 means are added to those shown in Figs. 21 and 22 by which this change in coacting or operative relations may be made to take place at will, held changed for the desired length of time and then changed back again or restored, without interfering with the operation of the means shown in these Figs. 21 and 22.

Switch devices B¹⁰, B¹¹, B¹² and B¹³, Figs. 21 to 25, consist of a pair of terminals for each device insulated from one another, normally open, and mounted on bars or controllers D¹⁰, D¹¹, D¹² and D¹³, respectively, which controllers are movable in bars Y¹⁰ and Y¹¹ mounted fixedly on frame F¹⁰, so as to move such pairs of terminals, as b¹⁰, b¹¹,

b¹² and b¹³, respectively, into and out of position to be closed and opened by being forced into contact and released therefrom, by pivotally mounted parts a²⁰, a²¹, a²² and a²³, respectively, when these parts are in the position in which part a²² is seen in Fig. 21, and where the terminals b¹² are seen in the inoperative position. These pivotally mounted parts, as a²⁰, a²¹, &c., are not carried by the controllers, as D¹⁰, D¹¹, &c., as are the parts a¹⁰, a¹¹, seen in Fig. 16 and parts a, a', &c., seen in Fig. 1, but are mounted on studs or supports as a²⁴, a²⁵, a²⁶ and a²⁷, which are fixed in bars, w¹⁰ and w¹¹ affixed to the frame F¹⁰ and they hold the parts, as a²⁰, a²¹ &c., in position to be moved in one way or the other by the movement of the carriage C³ past the switch devices, so long as the coacting or operative relations between such parts and actuating means are not changed, as shown at the right of Fig. 21, where parts a²¹ and a²³ are moved out of coacting relation with abutting portion e²¹ of the actuating means or carriage C³. These parts a²⁰, a²¹, a²² and a²³ may be normally held in the position mounted part a²⁰ is seen to occupy in Fig. 21, in the same manner that parts, as a, a', a², &c., are seen to be held in Figs. 1 to 7 and by similar means, that is by two arm springs, as seen in Fig. 22, where spring k¹⁰ is arranged relatively to part a²⁰ the same as corresponding springs are arranged in Figs. 2, 4, 5, 6, and 7 and to operate, as the springs, as k, k', &c., are described as operating to normally hold its part in a given position.

The controllers, D¹⁰, D¹¹, D¹² and D¹³ may be moved by springs, as S¹⁰ to bring the switch devices into operative condition, that is into position to be operated by mounted parts a²⁰, a²¹, a²² and a²³, Fig. 22 and, as S, S', &c., of Fig. 1, upon being released by armature, as m¹⁸, of magnet M¹⁸, and armatures, as m, m', &c., of magnets M, M', &c., of Figs. 22 and 1, respectively, which detain or hold such controllers out of operative position. The means shown in Figs. 21 and 23 for thus moving these controllers consist of rollers, as i⁴, i⁵, i⁶ and i⁷, mounted on the controllers, as shown and pivotally mounted spring pressed abutments or inclined surfaces I and I' mounted on and carried by the carriage C³. These abutments, as I and I', are movable in one direction against the stress of springs and are held against movement in the other direction by suitably arranged springs and stops the same as is the case with spring pressed pawls n⁶ and n⁷ of Figs. 8, 9 and 10, or pawls n²⁴ and n²⁵ of Figs. 15 and 17. These abutments I and I' like these pawls are each movable on the carriage to permit of their passing by an obstruction by moving on its support, as the carriage moves in one direction and is prevented from so moving, when the carriage moves in the other direction, and when pre-

vented from so moving it coacts with its respective obstruction to cause movement to take place of one relatively to the other, the only difference being that in one case the 5 pawl bodily moves, while in the other the obstruction bodily moves. This is due simply to which one is to be moved by the other in the coaction of the two and not in the manner of mounting the spring pressed part. 10 As the carriage C^3 moves upwardly spring pressed abutment I' engages with the rollers or abutments i^4 and i^6 , Figs. 21 and 22, when in engaging position, and moves controllers D^{10} and D^{12} back into the inoperative position 15 for the switches. When the carriage C^2 moves downwardly this spring pressed abutment I' passes by the rollers, as i^4 and i^6 , attached to controllers, as D^{10} and D^{12} , when such controllers are in the position controller 20 D^{12} is shown to be in, in Fig. 21, but engages with those of controllers in the position that controller D^{10} is in and moves against the stress of its spring and also moves on its pivot without moving or disturbing the controllers. Controller D^{10} is shown in Fig. 21 25 as being in the operative condition, that is, in position where the pair of terminals b^{10} will be closed by the upward movement of the actuating means or carriage C^3 causing 30 the abutment portion or surface thereof, as c^{20} , to move part a^{20} from the position there shown into a position corresponding to that occupied by part a^{22} . These terminals remain closed until part c^{20} has passed by part 35 a^{20} , when such part will be ready to return to the position it is now seen to occupy in Fig. 21, when spring pressed abutment I' , as it reaches roller i^4 , (in the upward movement of carriage C^3), engages therewith and 40 moves controller D^{10} and its switch device, B^{10} into a position corresponding to that occupied by controller D^{12} , Fig. 21. The relative positions of the spring pressed abutment I' and rollers i^4 and controller D^{10} is also 45 indicated in Fig. 22, where the parts are seen, as in Fig. 21, with switch device B^{10} in the operative condition, and movable into inoperative condition by the means provided for this purpose. 50 Vertically movable bars U and U' mounted on studs, as u^4 , u^5 , &c., are connected to a lever U^2 , (fulcrumed at its center) at substantially equal distances from such fulcrum, as shown, so as one end of the lever U^2 55 moves upwardly it moves the two bars simultaneously one bar moving upwardly and the other downwardly. When the lever U^2 reverses its movement the movement of the bars is also reversed. Each of these bars, 60 as U , U' , is provided with vertical slots which permit them to move up and down certain distances on studs, as u^4 , u^5 , &c., as shown. At each end of this lever U^2 an armature of a magnet is mounted, as m^{26} and 65 m^{27} of magnets M^{26} and M^{27} , which magnets

are to be energized, one at a time, that is, one is to be energized as the carriage C^3 moves upwardly and the other as the carriage is moved downwardly, and each, as it is energized, attracts its own armature moving lever U^2 on its fulcrum and moving bars U and U' , one up and the other down, as before explained. Lever U^2 has its fulcrum mounted on a plate, as U^3 , Fig. 21, or on a plate as U^4 , Fig. 24, or otherwise, accordingly as it is desired to construct the apparatus. When either plate, as U^3 or U^4 , is employed it may be mounted or affixed to the apparatus in any desired manner, as, for instance, as shown in Fig. 24, by studs or 70 otherwise, and such fulcrum may be fixedly or movably mounted on such plate, as desired. In Fig. 21 the fulcrum is shown as fixedly attached to plate U^3 and in Fig. 24 this fulcrum is movably mounted on plate U^4 . The plate U^4 is omitted from Fig. 23 for clearness of illustration, the studs by which plate or bar U^5 is slidably mounted on plate U^4 being seen in section. As shown the actuating means, or carriage, as C^3 , moves between magnets M^{26} and M^{27} and their armatures and lever U^2 is made in the form shown in plan view in Fig. 23^a, so as not to interfere with the movement of such carriage. In Figs. 23 and 24 the fulcrum of this lever U^2 is affixed to a movable piece or bar U^5 , mounted on plate U^4 to move vertically thereon, as clearly indicated in Fig. 23. This bar or slideable piece U^5 carries an armature m^{28} coacting with magnet M^{28} mounted on frame F^{10} , or elsewhere by any suitable means to hold it in place relatively to the other parts. A spring, as S^{20} , is connected at one end to this piece U^5 and to the other end to plate U^4 , Fig. 24, and its stress pulls piece U^5 upwardly as far as the slots therein and the studs u^8 and u^9 will permit and holds such piece firmly in its uppermost position, except when it is moved downwardly by the stress of such spring being overcome by 100 magnet M^{28} attracting armature m^{28} and moving piece U^5 downwardly into the position seen in full lines in Fig. 23, such piece moving from the position it is seen to occupy in Fig. 25, where it is seen in the position shown in dotted lines in Fig. 23. This piece U^5 may be locked or held automatically by means of a locking device or 105 detent V engaging with a part of it or the armature attached thereto, in the manner indicated in Figs. 23 and 25. This detent V is shown in Fig. 23, in full lines as engaged with the armature m^{28} in such manner as to lock piece U^5 in the position there seen in 110 full lines. This detent V is pivoted at V' , Figs. 23 and 25, and a spring S^{21} , Fig. 25, tends at all times to move detent V into engagement with armature m^{28} . This detent or locking device is moved against the stress of its spring S^{21} by a magnet, as M^{29} , mount- 115 120 125 130

ed on the apparatus by any suitable means, and armature, as m^{29} , attached to and carried by detent V , upon the energizing of this magnet M^{29} . These magnets M^{26} and M^{27} , seen in Figs. 21 and 23, and M^{28} and M^{29} , seen in Figs. 23, 24 and 25, may be energized from any desired source or sources, as, for instance, magnets M^{26} and M^{27} may be energized from source, as Z^2 , and magnets M^{28} and M^{29} from source, as Z^3 .

Circuit making and breaking contact devices, as v and v' are movably mounted on carriage C^3 and suitably insulated therefrom, one of which, as v' , is constructed to make electrical contact as the carriage begins to move downward, as the pawls are made to engage and change the operative relations of the switch devices and their actuating means, when arranged as seen in preceding figures, and the other movable contact device, as v , acts in a similar way when the carriage begins its upward movement, also as is the case when the pawls are arranged as in preceding figures. These contact devices, as v and v' are also so constructed that they pass by their companion fixed contacts without making electrical contact therewith; this is accomplished by providing them with insulating material on one side thereof, as shown, and therefore they do not energize the magnets in making physical contact with the fixed contacts, as v^2 , v^3 , v^4 and v^5 , except in one direction of movement of the carriage, on which these movable contact devices are mounted. In this respect the operation is in effect the same as in the case of the movable pawls in preceding figures. Also the result is the same in one case as in the other, that is, the change in the coacting or operative relations of the switch devices and that which operates them to close the circuits takes place immediately after the change in the direction of movement of the actuating means relatively to the switch devices, in both cases. In each case portions of either the switch devices or the actuating means are moved, one relatively to the other, in making this change in the coacting relations between such devices and actuating means, and the movement of either is equivalent to the movement of the other. These movable contact devices, as v and v' are suitably insulated from each other and the carriage and also normally held in a given relation to the carriage C^3 and their respective fixed contacts, as v^2 , v^3 , v^4 and v^5 , by two arm springs, as k^{12} and k^{13} , Fig. 22, acting thereon as the two arm springs, as k , k' , &c., act on parts, a , a' , &c., in Figs. 1 to 7, also as two arm spring k^{10} acts on part a^{20} , in Fig. 22, and as before explained. These movable contact devices, as v and v' , and the fixed contacts, as v^2 , v^3 , v^4 and v^5 are connected with magnets M^{26} and M^{27} and

source, as Z^2 , as follows; from contact device v , on carriage C^3 , a wire v^{10} leads to magnet M^{26} , from thence a wire v^{11} leads to source Z^2 ; from source Z^2 a wire v^{12} connects with fixed contacts v^2 and v^3 through wires v^{13} and v^{14} , respectively, and also with fixed contacts v^4 and v^5 by wires v^{15} and v^{16} , respectively; from contact device v' , on carriage C^3 , a wire v^{17} leads to magnet M^{27} , from thence by wire v^{28} to wire v^{11} which lead to source Z^2 .

The operation of changing the coacting or operative relations of the switch devices and the means which operate them is as follows: As carriage C^3 moves upwardly the insulated side of contact device v' on the carriage is brought into physical contact first with fixed contact v^3 and then with fixed contact v^2 , and passes by both without making electrical contact therewith, then upon a reversal in the direction of movement of carriage the non-insulated side of this device v' comes into contact with fixed contact v^2 again and as it wipes or moves past it electrical contact is made between device v' and contact v^2 which results in magnet M^{27} being energized and armature m^{27} moved into the position relatively to its magnet that the armature m^{26} occupies as seen in Fig. 21. This would bring the parts into positions opposite to that which they are seen to occupy in this Fig. 21, with mounted switch co-acting parts a^{20} and a^{21} , (there seen in their normal position,) into positions where portion c^{20} , of carriage C^3 , cannot engage therewith and close their respective pairs of terminals b^{10} and b^{12} . As the carriage continues its movement downward this contact device v' will make electrical contact with fixed contact v^3 , but as armature m^{27} has already been attracted out of the position seen in Fig. 21, a second energization of magnet M^{27} does not change its position and that of lever U^2 and no change in the coacting or operative relations of the switch devices and their operating means occurs. As the carriage moves downwardly the insulated side of contact device v comes into physical engagement with fixed contacts v^4 and v^5 , but electrical contact is not made therewith on this downward movement. Then upon the carriage reversing its direction of movement the non-insulated side of this contact device v contacts with the first fixed contact reached and the electrical contact between the two is made and magnet M^{26} is energized and armature m^{26} is attracted and the positions of the bars U and U' are reversed by the rocking of lever U^2 on its fulcrum into the positions seen in Fig. 21. This changes the coacting or operative relations of all the switch devices which are in operable condition, by moving or changing the positions of all the switch coacting parts, as a^{20} , a^{21} , &c.,

bringing those controlled by the bar U' into positions corresponding to those occupied by the corresponding parts controlled by the bar U and those controlled by the latter bar 5 into positions corresponding to that part a^{20} is seen to occupy in Fig. 21, then as the carriage continues its upward movement contact device v may contact with fixed contact v^4 , and as many others as desired, without making any change in the coacting relations of the switch devices and actuating means, one relatively to the other, as the parts are frictionally held in place except as moved by the armatures. From this it 10 will be seen that these contact devices, as v and v' physically engage with the fixed contacts in both directions of movement of the carriage, and that each is moved out of its normal position on each of such movements, 15 moving first in one direction and then in the other, just as is the case with parts, as a^{20} , a^{21} , &c. These bars U and U' , with lever U^2 and armatures, as before explained, 20 are all connected together and as they are moved by the energization of magnets M^{26} and M^{27} the lever U^2 rocks on its fulcrum and one bar and armature move toward one of such magnets and the other bar and armature move away from the other magnet. Whenever it is desired to change 25 the coacting or operative relations of the switch devices and the means which operate them at will, or by other means than the above rocking movement of lever U^2 on its fulcrum x , this may be done 30 by the movement of the vertically movable bar or piece U^5 , Figs. 23, 24 and 25, which is movably mounted on plate U^4 with a limited extent of movement on studs u^8 and u^9 , Fig. 23, seen in cross section. As 35 before explained this bar, as U^5 , has attached at its lower end an armature m^{28} , which, upon the energization of magnet M^{28} , is attracted moving such bar against the 40 stress of its spring S^{20} , which normally holds it in the position seen in dotted lines in Fig. 23 and in full lines in Fig. 25, and at the same time moving fulcrum x , of lever U^2 , downward into the position seen 45 in full lines in Fig. 23, thus bringing such lever into substantially a horizontal position, also as seen in full lines in said figure. Magnet M^{28} is connected, as shown, with 50 source of energy, as Z^3 , by wires v^{18} , v^{19} , v^{20} and v^{21} , wires v^{20} and v^{21} , connecting with push button P^{11} where the circuit is normally open. Upon operating push button P^{11} magnet M^{28} will be energized and bar U^5 and connected parts be moved 55 downward, as before explained. This downward movement of this lever and its fulcrum x brings both of the bars U and U' into substantially their lowermost positions, in the construction shown, and consequently brings 60 the coacting pieces, as a^{20} , a^{21} , &c., of the

switch devices into the positions that these pieces or parts a^{22} and a^{23} are seen to occupy in this Fig. 23, where all of such parts or pieces are so moved out of coacting or operative relations with the means which operate them, (to close the terminals of the switch devices,) that such means may move up and down past such coacting parts indefinitely without having effect thereon and consequently on the switch devices, until the normal relations of the two are reestablished. 70

In the normal operation of this form of apparatus one of the bars, as U and U' , is always in substantially its lowermost position, that is, at substantially its lowest limit of movement on the studs, as u^4 , u^5 , &c., and hence only one of these bars is movable to any substantial extent by the movement downward by fulcrum x . The one thus 80 movable is the one which at the moment is in the uppermost position. Upon the downward movement of fulcrum x and lever U^2 this lever fulcrums upon the one of its connections to bars U and U' , which is in the 85 lowermost position, because that bar is at its lowermost position and cannot move farther downward and the connection of such bar with lever, as U or U' . By reason of this lever thus fulcruming the one of the 90 armatures which is in the highest position moves downward into a position where the lever U^2 will be substantially at right angles to bars U and U' , as seen in Fig. 23, and the other armature will move upwardly 95 slightly, according to the difference between the two arms of the lever, at the moment. As bar U^5 is thus moved downwardly against the stress of spring S^{20} locking or holding 100 detent V , under the stress of its spring S^{21} , moves on its pivot V' into the position seen in full lines and into engagement with a portion of the armature m^{28} and such bar and fulcrum are held or locked in the 105 downward position until such detent is 110 moved against the stress of its spring S^{21} sufficiently to permit spring S^{20} to return bar U^5 to its normal position, as seen in dotted lines in Fig. 23. This detent or locking device V is moved against the stress of 115 spring S^{20} by armature m^{29} and magnet M^{29} , upon energizing the latter, which may be accomplished by connecting source of energy, as Z^3 , with push button, as P^{12} , and magnet by wires, as follows: from source Z^3 120 wires v^{18} and v^{22} lead to magnet M^{29} and wire v^{23} leads to push button P^{12} and from this push button wires v^{24} and v^{21} lead to source Z^3 again. In practice these push buttons, as P^{11} and P^{12} , are to be placed at convenient 125 points as desired and the circuits will be run in any desired manner to suit in any well known or desired way. The mode of operation will be the same no matter where these push buttons may be placed and the 130

circuits run to and from them to the source of energy and magnets. This return of this bar and connected parts to the positions seen in dotted lines in Fig. 23 restores such parts, so that the operation of changing the coacting or operative relations between the switch devices and actuating means by the energizing and deenergizing of magnets M^{26} and M^{27} may be resumed, as before explained. If desired the circuit connecting these magnets, as M^{26} and M^{27} , may be broken when it is desired to change the coacting relations of the switch devices and actuating means at will. This may be done by connecting the circuit or circuits of the magnets M^{26} and M^{27} with some form of circuit breaking device, as, for instance, such as is shown in Fig. 23, where wire v^1 connects, by a branch wire v^{25} with the movable arm x' of the circuit breaker X, which arm is normally in contact with point x^2 which connects by a branch wire v^{26} with wire v^{28} , which connects with magnets M^{26} and M^{27} , respectively, so that when arm x' is in contact with point x^2 , as seen in dotted lines, the circuit between these magnets and source of energy is completed at this point through circuit breaker X, but when the parts occupy the positions seen in full lines in Fig. 23 the circuit is broken and such magnets cannot be energized by the contact of devices, as v and v' with fixed contacts, as v^2 , v^3 , &c., on the up and down movements of carriage C³. This arm x' of circuit breaker X is in the form of an elbow lever and is connected with bar U^5 as shown, so as such bar moves this arm x' takes on a corresponding movement, breaking the circuit through branch wires, as v^{25} and v^{26} , on the downward movement of such bar and closing such circuit on the upward movement thereof.

The means, shown in Figs. 23, 24 and 25, which are additional to those seen in Figs. 21 and 22, are usable in connection with those seen in these latter figures, and they do not interfere with the operation of the parts connected with the lever U^2 , which form the means seen in Figs. 21 and 22, or in the normal or usual operation of opening and closing the circuit or circuits through operating some portion of the actuating means relatively to or past the switch device or devices. The means by which the bar or piece U^5 , fulcrum x and connected parts are moved, as above explained, remain inert or dormant in such normal operation of the means seen in Figs. 21 and 22 and hence do not interfere with such normal operation of not only the means shown in such two figures of the drawings, but also such means do not interfere with the normal operation of closing the circuit or circuits through the switch device or devices by the actuating means. When these additional

means, seen in Figs. 23, 24 and 25, are brought into operation, which can be done at the will of the operator, as heretofore explained, they control and suspend the operation of the means seen in Figs. 21 and 22, and they hold such operation suspended until brought out of operation and the parts released and restored to their normal positions. The holding device or detent V and its connected parts form holding means which hold or maintain the parts in their changed positions and are separately operable, that is, operable independently of the specific means by which the fulcrum x is moved, and like the holding means shown in preceding figures are operable by a force or forces other than that which actuated or moved the fulcrum x and connected parts movable therewith, hence such means are adapted to hold the parts in their changed positions independently of the force which moved them in changing the coacting or operative relations of the switch device or devices and actuating means, one relatively to the other.

The several embodiments of this invention herein set forth will naturally suggest to those skilled in the art other constructions and arrangements of parts than those herein shown, hence, I wish it to be understood that all constructions and arrangements of parts, which are combined together in the manner herein described, so as to have the mode of operation of the members or devices in the combination or combinations particularly pointed out in the claims hereunto annexed, are to be included within this invention.

What I claim as new is:—

1. In an elevator signal apparatus, in combination, a plurality of switch devices, actuating means adapted to move said devices to close a circuit through each device, and means comprising a movable part and means for shifting the same to change the coacting relations between said switch devices and said actuating means, one relatively to the other, and means for maintaining said changed relation during the relative movement of such means and devices in one direction.

2. In an elevator signal apparatus, in combination, a plurality of switch devices, means adapted to move past such device and actuate the same, changing means adapted to be displaced to change the coacting relations of the switch device and actuating means, and holding means adapted to engage with and continuously hold the changing means in its displaced position, before and after passing the individual switch devices.

3. In an elevator signal apparatus, in combination, a plurality of switch devices, means adapted to move past such devices in

succession and actuate the same, means adapted to change the coacting relations of the switch device and actuating means, and comprising a movable part, holding means comprising a holding member which is adapted to be moved into and out of holding position relatively to said movable part of the changing means, and means adapted to control said holding member.

10 4. In an elevator signal apparatus, in combination, a switch device, means adapted to move relatively to the switch device and actuate the same, means adapted to change the coacting relations of the switch device and actuating means, comprising an electrically controlled device, a circuit and operating means, and a holding device adapted to be moved into the path of movement of the said electrically controlled device and 15 hold the parts of said switch device in a fixed relation for a desired length of time.

5. In an elevator signal apparatus, in combination, a plurality of switch devices, means adapted to move relatively to the 20 switch device to pass the same in succession and actuate the same, means adapted to change the coacting relations of the switch device and actuating means, and holding means adapted to hold the parts in their 25 changed relation independently of the movement of the actuating means.

6. In an elevator signal apparatus, in combination, a plurality of switch devices, means adapted to move past the switch devices and actuate the same, some of said 30 switch devices being arranged to be actuated as such means moves in one direction and others as such means moves in the other direction, means adapted to change the coacting relations of the switch devices and 35 actuating means to the inoperative condition, and holding means adapted by the movement of a part thereof to maintain such inoperative condition in both directions of movement of the actuating means.

7. In an elevator signal apparatus, in combination, a plurality of switch devices, actuating means adapted to move past the switch devices and actuate the same, some 40 of said switch devices being arranged to be actuated while said means is moving in one direction, and others while said means is moving in the other direction, means adapted to change the coacting relations of the 45 switch devices and actuating means to a non-cooperative condition, and holding means composed in part of an electrical device, a circuit and operating means adapted to hold the said switch devices and actuating means in a non-cooperative relation at will, in both directions of movement of said 50 actuating means.

8. In an elevator signaling apparatus in combination, a plurality of switch devices 55 normally in an inoperative relation to their

actuating means, means adapted to bring such devices into operative relation to such means, actuating means adapted to move relatively to the switch devices and actuate the same when in operative relation, and means 60 a part of which is arranged at the main floor of the building adapted to change the operable relations between the switch devices when in operative condition and the actuating means.

9. In an elevator signal apparatus, in combination, a plurality of switch devices normally in an inoperative relation, means adapted to bring such devices into operative relation to their actuating means, actuating means adapted to move relatively to the switch device and actuate the same when in operative relation, and electrical means a part of which is arranged at and operable from the main floor adapted to change the 65 operative relations between the switch devices, when in operative relation, and the actuating means.

10. In an elevator signal apparatus, in combination, a signal device, a circuit therefor, a switch device normally in an inoperative relation with respect to its actuating means adapted to close such circuit, means adapted to bring such device into operable relation to its actuating means, actuating means adapted to move relatively to such device and actuate the same when in operative relation, controlling means a part of which is located at the main floor adapted to change the operable relation between the 70 switch device, when in operative relation, and the actuating means, and render the signal device inoperative until such operable relations are restored, and means adapted to restore such operable relations.

11. In a switch apparatus for an elevator signaling system, the combination of a signal device, a circuit therefor, a switch device normally in an inoperative relation with respect to its actuating means adapted to close such circuit, means adapted to bring such switch device into operable relation to its actuating means, actuating means adapted to move relatively to such device and actuate the same when in operative relation, controlling means a part of which is located at the starter's floor of the building adapted to change the operative relation between the switch device, when in operative relation, and the actuating means and holding means for said controlling means having an electro-magnet, a circuit and means adapted to close the circuit and energize the electro-magnet to release the controlling means and restore the operable relations of the switch 80 device and actuating means.

12. In a switch apparatus for an elevator signaling system, the combination of a signal device, a circuit therefor, a switch device normally in an inoperative relation with 85

respect to its actuating means adapted to close such circuit, means adapted to bring such switch device into operable relation to its actuating means, means adapted to move relatively to such device and actuate the same when in operable relation, controlling means a part of which is located at the starter's floor and provided with another part which is movable and adapted by its movement to change the operative relations of the switch device and said actuating means, when in operable condition, and holding means for said controlling means adapted to prevent the restoration of such operative relations until said holding means is operated to release the controlling means.

13. In a switch apparatus for an elevator signaling system the combination, of a signal device adapted to give signals to the operator of the car, a plurality of circuits therefor normally in an inoperable relation with respect to their being closed, means comprising a part arranged at each of several intermediate floors of the building and adapted to bring the circuits into operable relation preparatory to being closed for giving signals, circuit closing means movable correspondingly as the car moves and adapted by such movement to close the circuits and cause signals to be given only when the car is approaching the floor from which the signal has been given, and controlling means, a part of which is located at the starter's floor of the building adapted to change the operative relations of the circuits with respect to said circuit closing means, and render the signal device inoperative for giving signals.

14. In an elevator signaling apparatus in combination, an elevator car and shaft having signaling means for signaling to the operator of the car, means for operating the same to indicate to said operator at which of several intermediate floors to stop and comprising a passenger's controller controllable from each of said floors, and when operated from any such floor, adapted to cause the operator of the car to be signaled to stop at that floor, devices corresponding to each of said floors for restoring said signaling means to normal condition, and a starter's controller which is operable from the starting floor, and arranged to make the signaling means inoperative at will for a certain distance of travel.

15. In an elevator signaling apparatus in combination, an electrically operated visual signaling device carried by each car to signal the operator, a passenger's controller for each of several intermediate floors and each of which is operable from one of said floors and adapted to control the signaling device of each car, a part corresponding to the car arranged to move correspondingly to the car and causing the signaling device of that car

to be operated only when one of said controllers has been operated and that car is approaching the floor from which said controller has been operated, means for restoring said signaling device to normal relation, 70 and a controller for each car and signaling means located at a floor and arranged so that when operated, each cuts out the signaling device of its car only.

16. In an elevator signaling apparatus in combination, two elevator cars and shafts, each shaft having visual signaling means for signaling to the operator of the car of that shaft, means for operating the same to indicate to said operator at which of several intermediate floors to stop and comprising a passenger's controller operable from each of said floors and, when operated from any such floor, adapted to cause the operators of both cars to be signaled to stop at that floor, devices corresponding to each of said floors for restoring said signaling means of both cars to normal condition, and a starter's controller for each car which is operable from the starting floor and either of which, when operated, makes the signaling means of only its shaft inoperative for a certain distance of travel.

17. In an elevator signaling apparatus in combination, two elevator cars and shafts, each shaft having visual signaling means for signaling to the operator of the car of that shaft, means for operating the same to indicate to said operator at which of several intermediate floors to stop and comprising a "passenger's controller" operable from each of said floors and, when operated from any such floor, adapted to cause the operators of both cars to be signaled to stop at that floor, and also comprising a part for each car moved correspondingly to the movement of its car and adapted to prevent a signal for any such floor being given except when a car is approaching that floor, devices corresponding to each of said floors for restoring said signaling means of both cars to normal condition, and a starter's controller for each car which is operable from the starting floor and either of which, when operated, makes the signaling means of only its shaft inoperative for a certain distance of travel.

18. In an elevator signaling apparatus in combination, two elevator cars and shafts, an electrically operated visual signal carried by each car, a passenger's controller for each of several intermediate floors and each of which is operable from one of said floors and adapted to control the signals of both cars, a part for each car moved correspondingly to the movement of its car and causing the signal of that car to be operative only when one of said controllers has been operated and that car is approaching the floor from which said controller has been operated, devices for each car corresponding to 130

each of said floors for restoring the signals of both cars to normal condition, and a starter's controller for each car operable from the starting floor and either of which, 5 when operated, makes the signal of only its car inoperative.

19. In an elevator signaling apparatus in combination, two elevator cars and shafts, an electrically operated visual signal carried by each car, a passenger's controller for each of several intermediate floors and each of which is operable from one of said floors and adapted to control the signals of both cars, a part for each car moved correspondingly to the movement of its car and causing the signal of that car to be operative only when one of said controllers has been operated and that car is approaching the floor from which said controller has been operated, devices for each car corresponding to each of said floors for restoring the signals of both cars to normal condition and automatically operated by the movement of said cars, and a starter's controller for each car operable from the starting floor and either of which, when operated, makes the signal of only its car inoperative.

20. In a car-signal apparatus, in combination, a car, a plurality of signal circuits corresponding to the different floors, a traveler arranged to move correspondingly with the car, a movable member carried by said traveler, circuit closers for said circuits adapted to be moved into the path of said movable member to enable the same to move the circuit closers to close the circuits, and means for controlling said movable member from a floor.

21. In a car-signal apparatus, in combination, a car, a plurality of signal circuits corresponding to the different floors, a traveler arranged to move correspondingly with the car, a movable member carried by said traveler, circuit closers for said circuits adapted to be moved into the path of said movable member to enable the same to move the circuit closers to close the circuits and means for controlling said movable member from a floor, said signal circuits corresponding to the up and down directions of the car, and mechanical means for shifting said movable member to correspond with the car's direction so that it closes only the circuits corresponding to the direction of movement of the car.

22. In a car-signal apparatus, in combination, a car, a plurality of signal circuits corresponding to the different floors, a traveler arranged to move correspondingly with the car, a movable member carried by said traveler, circuit closers for said circuits adapted to be moved into the path of said movable member to enable the same to move the circuit closers to close the circuits, said signal

circuits corresponding to the up and down 65 directions of the car, mechanical means for shifting said movable member to correspond with the car's direction so that it closes only the circuits corresponding to the direction of movement of the car, and means for rendering said movable member temporarily inoperative.

23. In a car-signal apparatus, in combination, a car, a plurality of signal circuits corresponding to the different floors, a traveler 75 arranged to move correspondingly with the car, a movable member carried by said traveler, circuit closers for said circuits adapted to be moved into the path of said movable member to enable the same to move the circuit closers to close the circuits, said signal circuits corresponding to the up and down directions of the car, and mechanical means for shifting said movable member to correspond with the car's direction so that it 85 closes only the circuits corresponding to the direction of movement of the car, and a circuit having means for rendering said movable member inoperative while said circuit remains closed.

24. In a car-signal apparatus, in combination, a car, a plurality of signal circuits corresponding to the different floors, a traveler arranged to move correspondingly with the car, a movable member carried by said traveler, circuit closers for said circuits adapted to be moved into the path of said movable member to enable the same to move the circuit closers to close the circuits, said signal circuits corresponding to the up and down 100 directions of the car, and mechanical means for shifting said movable member to correspond with the car's direction so that it closes only the circuits corresponding to the direction of movement of the car, and a circuit having means for rendering said movable member inoperative while said circuit remains closed, and means controlled by said circuit for locking said movable member inoperative to enable it to pass said circuit 110 closers without actuating the same.

25. In an elevator signal apparatus, in combination, a car, a plurality of circuits corresponding to the different floors, a traveler adapted to move correspondingly to said 115 car, said circuits including a signal device in said car, means corresponding to the different floors for closing said circuits, a laterally movable shoe carried by said traveler adapted to actuate said last means, and electrical 120 means for controlling the position of said shoe so that said shoe may or may not close said circuits, said circuits corresponding to the up and down direction of said car respectively, automatic mechanical means normally adapted to shift said shoe laterally 125 into different positions to correspond with the directions of movement of said car, said

1,112,378

electrical controlling means for said shoe being independent of said automatic mechanical means.

26. In an elevator signal apparatus, in combination, a car, a plurality of circuits corresponding to the different floors, a traveler adapted to move correspondingly to said car, said circuits including a signal device in said car, means corresponding to the different floors for closing said circuits, a laterally movable shoe carried by said traveler adapted to actuate said last means, and elec-

trical means for controlling the position of said shoe so that said shoe may or may not close said circuits, said electrical controlling means including an electric locking device for holding the said shoe in its inactive position, and means including a pole changer for controlling said locking means.

HENRY F. NEWBURY.

Copies of this patent may be obtained for five cents each, by addressing the "Commissioner of Patents, Washington, D. C."

It is hereby certified that in Letters Patent No. 1,112,378, granted September 29, 1914, upon the application of Henry F. Newbury, of New York, N. Y., for an improvement in "Switching Apparatus," errors appear in the printed specification requiring correction as follows: Page 11, line 111, for the words "each on" read *on each*; same page, same line, strike out the word "the"; and that the said Letters Patent should be read with these corrections therein that the same may conform to the record of the case in the Patent Office.

Signed and sealed this 10th day of November, A. D., 1914.

[SEAL.]

R. F. WHITEHEAD,

Acting Commissioner of Patents.
